[57] CLAIM

The ornamental design for a vending vehicle body for selling and dispensing frozen deserts or the like, as shown and described.

DESCRIPTION

FIG. 1 is a perspective view of the front and one side of a vending vehicle body for selling and dispensing frozen deserts or the like showing my new design; FIG. 2 is a perspective view thereof showing the rear and side shown in FIG. 1.

The broken lines in the drawing are for illustrative purposes only.

The side opposite to that shown in the drawings is a mirror image thereof.

FIG. 1
